V. ODQUIST

VARNISH CAN LABEL

Filed Dec. 6, 1920

FIG. 1

FIG. 2

FIG. 3

Inventor:
Victor Odquist
By Munday, Clarke & Carpenter
Atty.

UNITED STATES PATENT OFFICE.

VICTOR ODQUIST, OF YONKERS, NEW YORK, ASSIGNOR TO AMERICAN CAN COMPANY, OF NEW YORK, N. Y., A CORPORATION OF NEW JERSEY.

VARNISH-CAN LABEL.

Application filed December 6, 1920. Serial No. 428,499.

To all whom it may concern:

Be it known that I, VICTOR ODQUIST, a citizen of the United States, residing in Yonkers, in the county of Westchester and 5 State of New York, have invented a new and useful Improvement in Varnish-Can Labels, of which the following is a specification.

10 My invention relates in general to containers, such as varnish cans and the like, and has more particular reference to handles therefor having labels which may be attached or removed at will.

15 A principal object of the invention is the provision of means whereby labels having any desired inscription may be attached to such containers after they are completely assembled, thus permitting the making up of quantities of the containers prior to the receipt of orders therefor, and applying the 20 labels at the time they are delivered.

25 A further object of the invention is the provision of a label, and means for attaching the same to containers of the type described, which will permit interchanging at any time, thereby making it possible to use alternately or at will labels containing an address or identification of the contents of the cans or having other desired marking.

30 Another object of the invention is the provision of a label and holding means therefor having these and other advantages, and at the same time being of simple construction and permitting easy attachment by hand.

35 Other objects and advantages of the invention will be apparent as it is better understood from the following description when considered in connection with the accompanying drawing illustrating a preferred embodiment thereof.

40 Referring to the drawings:

Figure 1 is a perspective view of the top of a container having the handle and label attached;

45 Fig. 2 is a detail view of the handle and attached label; and

Fig. 3 is a sectional view taken on the line 3—3 in Fig. 2.

50 On the drawings which illustrate an embodiment of my invention, it will be noted that a handle 11 is attached to the top 12 of a container 13. All of these parts may be

of any usual or preferred material or construction, the handle here being shown as having curved or rounded corners 14 and 55 having its flanged ends 15 soldered onto the material of the top.

The label 16, of course, need not be of any particular type, but normally will be merely a plain strip of suitable material having any desired inscription. It is attached to the handle by means of integral bent-over cleats or fingers 17, which, preferably, are stamped from the material of the handle from beneath in order to leave a 60 smooth surface on the under side of said handle and to aid in forming a heel or stop 18 in the cleats for the edges 19 of the label to rest against. The cleats may be bent upwardly by a knife blade or otherwise to permit placing the label in position, after which they are bent downwardly over the surface of said label to secure it in place. It will be readily seen that this may be done at any 65 time and with the handle attached to the 70 container, thus subserving the purposes set forth above. The edges 21 on the sides of the handle are upturned or beaded as shown in Figs. 1 and 2, thereby providing additional means for holding the label in place. 75 When the bead or flange is rolled or bent inwardly from the top, the longitudinal edges of said label may be inserted therebeneath, thus preventing lateral movement or too easy removal even though the cleats 80 should be inadvertently bent from their holding position. Said beads stiffen and strengthen the handle and also guard said cleats from scratching or bruising the hand and from catching on other objects. 85

90 It will be manifest that my invention is susceptible of very practical use both by shippers and users of containers of this general type, since it makes possible the use interchangeably of various kinds of labels 95 which may be attached or removed at any time, and obviates the necessity of attaching the label at the time of forming the handle.

100 It is thought that the invention and many of its attendant advantages will be understood from the foregoing description, and it will be apparent that various changes may be made in the form, construction and arrangement of the parts without departing

from the spirit and scope of the invention or sacrificing all of its material advantages, the form hereinbefore described being merely a preferred embodiment thereof.

5 I claim:

A label holder in a sheet metal container handle, which consists of two curled or

beaded edges of said handle to serve as side holding means and integral struck up parts of said handle material to serve as end holding means for a label positioned between said edges and said struck up parts. ¹⁰

VICTOR ODQUIST.
